BRICK OR BLOCK CASTING MACHINE

Robert S. Reed, Three Rivers, Mich.

Application October 18, 1946, Serial No. 704,246

4 Claims. (Cl. 25—41)

1

This invention relates to improvements in brick or block casting machines.

The principal objects of this invention are:

First, to provide a machine for casting individual bricks or building blocks with a vibratory packing system which is both compact and easily operated.

Second, to provide a brick casting machine in which there are no rotating or reciprocating parts in the vibratory system to become worn or get out of order.

Third, to provide a brick casting machine in which the vibrating machinery and controls therefor are effectively enclosed and protected against contact with mortar and water.

Fourth, to provide a casting machine in which the amplitude of vibration is adjusted by an electrical control.

Fifth, to provide a casting machine which will cast a plurality of bricks on a simple removable pallet so that the handling and the curing of the bricks after casting is facilitated.

Sixth, to provide a casting machine which is easily adaptable to making either a plurality of bricks or one or more larger blocks.

Other objects and advantages pertaining to the details and economies of the invention will be apparent from a consideration of the following description. The drawings, of which there are two sheets, illustrate a preferred form of casting machines.

Fig. 1 is a perspective view of my casting machine in closed or vibrating position.

Fig. 2 is a fragmentary perspective view of the brick forming section of my machine in partially open position showing completed bricks in place thereon.

Fig. 3 is a fragmentary cross-sectional view along the plane 3—3 in Fig. 4.

Fig. 4 is a fragmentary plan view of my casting machine in closed position.

Fig. 5 is an enlarged fragmentary cross-sectional view similar to Fig. 3 but showing the machine in an optional arrangement for making large blocks.

In the drawings the reference numeral 1 indicates the base of my casting machine which consists of a welded angle iron frame and sheet metal panels enclosing suitable power supply and regulating mechanism at 2 to be more particularly described presently. A heavy metal plate 1A welded to the top of the frame adds rigidity to the frame and protects the regulating mechanism.

Mounted on the base 1 on four bolts and coil

2

springs 3 are a pair of channel support members 4 which form supports for the side plates 5 connected thereto by the brackets 6. The side plates have welded thereto vertical angle members 7 which extend above the center of the side plates and form supports for the ends of a backing plate 8. Angle brackets 9 (see Figs. 1 and 5) secured to the insides of side plates 5 form supports for a bed plate 10 which extends horizontally between the side plates forwardly of the vertical angles 7. The bed plate 10 has two or more wooden riser blocks 11 secured to its upper surface which form supports for the removable pallet 12 freely supported thereon.

The backing plate 8 is vertically slotted as at 13 through approximately the upper half of its width to pass eight divider plates 14 which extend forwardly across the top surface of the pallet 12. The rear ends of the divider plates are secured to and spaced along a threaded spacer bolt 15, their spacing being determined by nuts 16 threaded on the bolt on each side of each divider plate. The spacer bolt 15 is supported at its ends in guide plates 17 which define horizontal slots 18 in which the spacer bolt is arranged to be translated forwardly and backwardly. The forward edges of the guide plates 17 are flanged inwardly as at 19 and secured to the opposite sides of the vertical angle members 7 from the backing plate 8. Secured to each end of the spacer bolt 15 are levers 20 having their lower ends pivotally mounted as at 21 to the side plates 5. The divider plates are thus arranged to reciprocate forwardly and backwardly through the slots 13 in the back plate and over the pallet 12 as indicated by the dotted lines at 22 in Fig. 3 by movement of the levers 20 and bolt 15.

Connected to the levers 20 intermediate of the ends thereof are a pair of links 23 which extend forwardly of the machine and have their front ends secured to the bottom of front levers 24 as at 25. The levers 24 are pivotally supported as at 26 on the forward corners of the side plates 5. The front levers 24 have an angular shaped cross section at their upper ends and are secured to a front plate 27 which is vertically slotted as at 28 corresponding to the slots in the backing plate 8. The handle 29 secured to the front plate by the Z-shaped brackets 30 is operable to tip the front plate 27 and front levers 24 forwardly about the pivots 26. Forward motion of the handle 29 will throw the links 23 and the rear levers 20 to the rear of the machine simultaneously causing the spacer bolt to be

moved to the rear of the slots 18 in the guide plates and drawing the divider plates through the slots 13 away from the pallet 12, thus leaving the bricks 31 freely supported on the pallet and spaced so that air may circulate therearound for proper curing of the mortar.

The mechanism for vibrating the bed plate 10 and the pallet 12 carried thereon is most clearly illustrated in Fig. 3 and consists of supporting brackets 32 secured to the under side of the bed plate and directly connected to the middle of the longitudinal springs 33 by studs 34 which extend downwardly to the ends of a transverse spring 35. The ends of the longitudinal springs and the middle of the transverse spring are connected to lower brackets 36. The support brackets 32 have clamped therebetween a series of laminated core plates 37 which are slightly spaced from and cooperate with a series of laminated armature plates 38 clamped between the lower brackets 36 to complete a magnetic path for flux set up by a magnetic coil not shown. The coil is connected through an electrical cable 39 (see Fig. 1) to the power supply and control mechanism 2 in the base of the machine. The control mechanism includes a rectifier and rheostat for converting alternating current to a pulsating current of variable amplitude to cause the core 37 and armature 38 to be attracted toward each other once during each cycle of the alternating current thus vibrating the bed plate 10 and the pallet carried thereon. Varying the amount of current in the coil by adjusting the rheostat knob 40 changes the amplitude of vibration making the machine quickly adaptable to various weights of aggregate. A foot operated lever or pedal switch 41 connected to the control mechanism by electrical cables 42 is provided so that the operator of the machine may have both hands free to manipulate the handle 29. Sheet metal panels 43 clamped between the under-side of the bed plate and the brackets 32 entirely enclose the vibrating equipment and protect it from mortar and dust. The details of the control mechanism 2 and vibrating mechanism are not described or illustrated in greater detail as these parts are standard commercial products sold under the trade name of Syntron by the Syntron Company of Homer City, Pennsylvania.

In operation the handle will be drawn forwardly exposing the riser blocks 11 so that a new pallet 12 may be placed thereon. The handle is then thrown forwardly drawing the divider plates forwardly over the pallet and into engagement with the slots in the front plate 27 to maintain the vertical alignment of the dividers.

A quantity of mortar may then be poured into the spaces between the divider plates sufficient to form the bricks and the vibrating mechanism started by actuation of the foot pedal 44. As mentioned before the machine is easily adaptable to mix aggregates of different weight by merely adjusting the rheostat control knob 40, it being well known that light weight aggregates must be vibrated with less amplitude than heavy aggregate which requires a longer travel or amplitude of vibration to be compacted properly. The speed and advantages of vibratory casting of cement mortar are well known and need no further description and the molding operation can be completed in a very short time after which the operator will again draw the handle forwardly simultaneously withdrawing the divider plates and permitting the removal of the pallet and the completed bricks. The smooth pallet,

front and back plates and divider plates give the bricks a smooth surface with square sharp corners. When operated efficiently my machine can complete four cycles of operation a minute, or as shown in the drawings, can form 28 bricks a minute.

With the alternate arrangement shown in Fig. 5 one or more of the interior divider plates are rotated backwardly on the spacer bolt and allowed to hang freely as at 14A. The end divider plates then cooperate with the front plate 27 and backing plate 12 to define one or more larger casting cavities for making larger blocks.

Obviously variation in the size and spacing of the front plate, backing plate and divider plates will provide a varying number and size of bricks or blocks cast. The machine is made almost entirely of standard plate and angle stock and so is inexpensive to manufacture.

Having thus described my invention, what I claim as new and desire to secure by Letters Patent, is:

1. A brick casting machine comprising a base, a pair of laterally spaced channel-shaped supports yieldingly mounted on said base, vertical side plates on said supports, a vertical member carried near the center of each side plate and extending thereabove, a horizontal bed plate supported on said side plates forwardly of said vertical members and adapted to freely support a removable pallet, a magnetic vibrator secured to the under side of said bed plate, a backing plate extending between said vertical members and behind said bed plate, said backing plate defining a plurality of vertical slots from the upper edge thereof, guide plates secured to said vertical members and extending to the rear of said backing plate, said guide plates defining horizontal slots, a threaded spacer bar having its ends translatable along said slots and extending therethrough, a plurality of divider plates having their rear ends secured between nuts on said spacer bar and extending through said slots in said backing plate, rear lever members secured to the ends of said spacer bar and pivotally connected to said side plates, front levers pivotally mounted on said side plates near the front thereof, a front plate secured between said front levers and defining a plurality of vertical slots in the planes of said slots in said backing plate, links pivotally connected between said front levers and rear levers, angle shaped brackets secured to said front plate and engageable with the top of said backing plate to stop the rearward motion of said front plate in a position parallel to said backing plate, an operating handle connected between said brackets, and power supply mechanism for said vibrator enclosed in said base.

2. A brick casting machine comprising a base, a pair of laterally spaced support members yieldingly supported on said base, vertical side plates supported on said support members, a vertical member carried near the center of each side plate and extending thereabove, a transverse bed plate supported on said side plates forwardly of said vertical members and adapted to freely support a removable pallet, a magnetic vibrator secured to the under side of said transverse support plate, a backing plate extending between said vertical members and behind said bed plate, said backing plate defining a plurality of vertical slots, guide plates secured to said vertical members and extending to the rear thereof, said guide plates defining elongated slots, a spacer

bar having its ends translatable along said slots and extending therebetween, a plurality of divider plates having their rear ends pivotally secured to said spacer bar and extending through said slots in said backing plate, rear lever members secured to said spacer bar and pivotally connected to said side plates, front levers pivotally mounted on said side plates near the front thereof, a front plate secured between said front levers and defining a plurality of vertical slots coplanar with said slots in said backing plate, links pivotally connected between said front levers and rear levers, brackets secured to said front plate, an operating handle connected between said brackets, and power supply mechanism for said vibrator enclosed in said base.

3. A brick casting machine comprising a support including a vertical backing plate and horizontal bed plate, said backing plate defining a plurality of vertical slots, a slotted front plate pivotally supported on said support and arranged to be tilted into vertical position in front of said bed plate, a transverse spacer bar slidably supported on said support and arranged to be moved toward and away from the rear of said backing plate in parallel relationship thereto, a plurality of vertical divider plates having their rear ends pivotally secured to said spacer bar whereby said divider plates can be selectively positioned in forward projecting position through said slots in said backing plate for translation through said backing plate into engagement with the slots in said front plate and over the top of said bed plate or in depending position behind said backing plate, and linkage connecting said front plate and spacer bar operative to effect simultaneous forward movement of said front plate and rearward movement of said spacer bar and divider plates.

4. A brick casting machine comprising a base, a support yieldingly mounted on said base and including a vertical backing plate and horizontal bed plate adjacent the front lower edge of said backing plate, said backing plate defining a plurality of vertical slots, magnetic vibrating equipment secured to the under side of said bed plate, power supply and control mechanism for said vibrating mechanism enclosed in said base, a slotted front plate pivotally supported on said support and arranged to be tilted into vertical position in front of said bed plate, a transverse spacer bar slidably supported on said support and arranged to be moved toward and away from said backing plate, a plurality of vertical divider plates having their rear ends pivotally secured to said spacer bar and translatable therewith through said backing plate into engagement with the slots in said front plate, and linkage connecting said front plate and spacer bar operative to effect simultaneous forward movement of said front plate and rearward movement of said spacer bar and divider plates.
